UNITED STATES PATENT OFFICE.

OSCAR A. SWINGLE AND THOMAS J. MANGAN, OF BINGHAMTON, NEW YORK, ASSIGNEES
TO THE WILKINSON MANUFACTURING CO., OF BINGHAMTON, NEW YORK, A COR-
PORATION OF NEW YORK.

CHILD'S VEHICLE.

1,223,009.

Specification of Letters Patent. Patented Apr. 17, 1917.

Application filed November 15, 1916. Serial No. 131,484.

To all whom it may concern:

Be it known that we, OSCAR A. SWINGLE and THOMAS J. MANGAN, citizens of the United States, and residents of Binghamton, New York, have invented certain new and useful Improvements in Children's Vehicles, of which the following is a specification.

Our invention relates to the class of toys adapted for the use of small children in which a body is supported on wheels, the front wheels being provided with a head having steering means.

It is the object of our invention to make a very simple and compact form of device; of exceptional strength; of an attractive character and one very simply made and easily manipulated.

In the accompanying drawing:

Figure 1 is a side elevation of our improved device.

Fig. 2 is a section on line 2—2 Fig. 1.

Fig. 3 is a plan view.

Our improved device presents three very important advantages, in that the head is made of laminated strips, which gives the maximum of strength and prevents warping and splitting; the pair of wheels at the front tends to preserve the balance of the vehicle as distinguished from a single wheel and the disk extending from the lower part of the steering head provides a support for the limbs of the child when coasting.

The body comprises a seat A to which the back wheels are rigidly secured by a block B through the lower end of which the axle C passes, the wheels D being supported by this axle. A brace E extends between the block B and the under-part of the seat to add to the strength of the structure. The front end of the device is substantially circular from the point where it expands from

the reduced central portion F and is provided with a central opening to which is fitted a post α , to which is connected the head b made up of laminated sections or veneers suitably secured together, ornamented to imitate a horse's head. Two handles c project outwardly from the steering head near the upper end and the child by grasping these handles steers the head and with it the front wheels to direct the vehicle in the direction he desires to go. A disk d is secured to the bottom of the head and this bears directly upon the surface of the front end of the body turning thereon and forming a ledge on each side of the head for the support of the child's limbs in coasting and at the same time giving support to the head itself in its turning movement and taking the strain from the post α . The post projects below the lower face of the body where it is surrounded by a metal washer e . The two front wheels are arranged preferably close together, being supported on a metal axle or pin, which passes through the reduced end of a hanger f and the upper part of this hanger is recessed to receive the end of the post α being secured thereto by a screw-threaded bolt passing through the hanger and post and having a nut on the end to hold the parts in place.

What we claim is:

A child's vehicle comprising a body portion, wheels supporting the same, and a turning head having a disk secured to the bottom thereof and interposed between the head and the face of the body forming a support for the child's limbs in coasting, substantially as described.

OSCAR A. SWINGLE.
THOMAS J. MANGAN.
